Patented Dec. 11, 1973

229,565

BAFFLED LOUD-SPEAKER

Charles Légorju, Montreuil, France, assignor to
Societe Audax, Montreuil, France

Filed Mar. 10, 1972, Ser. No. 233,860

Claims priority, application France Sept. 14, 1971

Term of patent 7 years

Int. Cl. D14—01

U.S. Cl. D26—14 G

Fig. 1

Fig. 2

Fig. 3

FIG. 1 is a top and side perspective view of a baffled loud-speaker, showing my new design, the appearance being the same from all sides;

FIG. 2 is a bottom and side perspective view; and

FIG. 3 is a top and side perspective view thereof from a different angle.

I claim:

The ornamental design for a "baffled loud-speaker," as shown and described.
